Patented Mar. 6, 1923.

1,447,271

UNITED STATES PATENT OFFICE.

JOSEPH SOSS, OF NEW YORK, N. Y.

DOOR-ALIGNING DEVICE.

Application filed April 26, 1921. Serial No. 464,644.

To all whom it may concern:

Be it known that I, JOSEPH Soss, a citizen of the United States, and residing at New York, in the county of New York and State 5 of New York, have invented certain new and useful Improvements in Door-Aligning Devices, of which the following is a specification, such as will enable those skilled in the art to which it appertains to make and use 10 the same.

This invention relates to aligning devices for use in connection with doors and principally doors of motor vehicles, and the object of the invention is to provide a device of the 15 class specified which is composed of two parts or units, one of which is secured to the door frame and the other of which is secured to and carried by the door, and said parts being adapted to cooperate with each other 20 to properly align and support the door in the door frame or body of a vehicle as the case may be; a further object being to provide a device of the class and for the purpose specified which is so constructed as to release or 25 partially open the door when unlocked or unlatched thus facilitating the free and easy manipulation of the door in the operation of opening the same; and with these and other objects in view the invention consists in a 30 device of the class specified which is simple in construction, efficient in use and which is constructed as hereinafter described and claimed.

The invention is fully disclosed in the following specification, of which the accompanying drawing forms a part, in which the separate parts of my improvement are designated by suitable reference characters in each of the views, and in which:—

40 Fig. 1 is a horizontal sectional view of a part of a door and door frame or body, and showing one form of my improved aligning device mounted in connection with said door and door frame or body;

45 Fig. 2 a partial section on the line 2—2 of Fig. 1;

Fig. 3 a sectional detail view of part of the construction which I employ and showing a modification;

50 Fig. 4 a view similar to Fig. 3 but showing another form of construction;

Fig. 5 a view similar to Figs. 3 and 4 but showing another modification;

55 Fig. 6 a partial section on the line 6—6 of Fig. 5;

Fig. 7 a diagrammatic view indicating the

method of aligning a door in a framework or support by my improved device as shown in Figs. 1 to 6 inclusive; and,

Fig. 8 a view similar to Fig. 7 but showing a modification.

In Figs. 1 and 2 of the drawing I have shown at 10 a part of a door framework, or the body of a motor vehicle, as the case may be, and at 11 a part of a door mounted in 65 said framework. My improved aligning device is preferably composed of separate parts or units 12 and 13, the unit 12 being mounted in the framework 10, while the unit 13 is mounted in connection with the door 11 and 70 is movable therewith.

The unit 12 of my device comprises a casing 14 open at one side as shown at 15 and at the front as shown at 16, and mounted in the casing is a spring socket member 17 75 which forms a closure for the front opening 16 of said casing.

The socket member 17, in the form of construction shown, in Figs. 1 and 2, is composed of a strip of metal fashioned to form 80 angular end portions 18 which fit within the top and bottom portions of the casing 14, and said strip is fashioned centrally to form an inwardly directed semi-circular loop 19 at the opposite sides of which are outwardly 85 and inwardly curved loop members 20. The unit 12 is adapted to be countersunk in the framework 10 and is secured in position by screws or similar attaching devices 21 passed through the casing 14 and into said framework and two of these screws serve to aid in holding the spring socket member 17 in proper position, as will be apparent on a consideration of Fig. 2 of the drawing.

The unit 13 of my device comprises, in the 90 form of construction shown, an elongated plate 22 countersunk in and secured to the free side of the door 11 by screws or similar devices 23, and said plate is provided centrally with a pair of outwardly directed ears 24 at the opposite sides thereof, and a pin or shaft 25 is secured in said ears and on which an antifriction roller 26 is rotatably mounted between the ears 24 as clearly shown in Figs. 1 and 2 of the drawing.

In Fig. 3 of the drawing, I have shown a slight modification in which I employ two steel balls 27 which are adapted to partially protrude through apertures 28 in the socket member 17, and in this form of construction I also employ a resilient backing member 29 for the socket member 17 as well as

the balls 27, which backing member fills the entire cavity or opening within the casing 14, as clearly shown in said figure, and it will be apparent that the balls 27 are capable of 5 inward movement independent of the socket member 17 when the anti-friction roller 26 passes into said socket member in the operation of closing the door.

In Fig. 4 I have shown a modification in 10 which I substitute for the backing member 29 shown in Fig. 3 a sheet metal spring backing member 20 which is fashioned to conform with the general shape of the socket member 17, and which is also provided with 15 arc-shaped depressions 31 to form seats for the balls 27.

In Figs. 5 and 6 of the drawing I have shown another modification in which the socket member 17 is fashioned to form two 20 oppositely disposed cylindrical bearings 32 in which anti-friction rollers 33 are adapted to be mounted. The bearings 32 are formed, in the construction shown, by bending predetermined parts of the strip of spring metal 25 from which the socket member 17 is formed inwardly as shown at 34 and bending other parts thereof outwardly as shown at 35 in Figs. 5 and 6 of the drawing thus exposing 30 the central portion of the rollers 33 within the socket of the member 17.

My improved device, as hereinbefore stated, is adapted to function primarily to properly align a door in a door framework, or to keep the door in proper alignment at all times and 35 to prevent the sagging or misplacement thereof, and further by reason of the resilient qualities of the socket member employed I facilitate the opening of the door when unlocked or unlatched, the device functioning 40 to move the door outwardly or to partially open the same; and further it will be apparent that my improved device will also operate to support the door in the framework, at all times, under tension, thus preventing 45 the rattling of said door in the framework, especially when my improved device is employed in connection with the doors and body of motor cars.

In Fig. 7 I have illustrated in full and 50 dotted lines the anti-friction roller 26, in two positions from either of which it may enter the socket member 17 to align the door in the frame and with the roller 26 in the position shown in full lines in said figure, the 55 door will be raised into the socket member 17 while with the position of said roller shown in the dotted lines, the door will be lowered into said socket member.

In Fig. 8 of the drawing, I have shown a 60 slight modification which consists in providing a socket member adapted to be mounted in connection with the door frame of a door to raise the door in said frame for aligning purposes, it being understood that 65 in most cases the outer or free side portion

of the door usually sags, and it will be usually necessary to raise the door rather than to move it downwardly for aligning purposes. In other words, I am not necessarily limited to the specific shape and construction 70 of the socket of the unit 12 as shown in Figs. 1 to 6 inclusive, nor am I limited to the specific construction of the unit 13 herein shown and described, and various changes in and modifications of the construction 75 herein shown and described may be made, within the scope of the appended claims, without departing from the spirit of my invention or sacrificing its advantages.

Having fully described my invention, 80 what I claim as new and desire to secure by Letters Patent, is:—

1. A device of the class described for use in connection with a swinging member mounted in a stationary support, said device being 85 composed of separate units, one of which is mounted in connection with the stationary support and the other of which is mounted in connection with the swinging member, one of said units being provided with a 90 socket and the other unit with anti-friction means adapted to enter said socket.

2. A device of the class described for use in connection with a swinging member mounted in a stationary support, said device being 95 composed of separate units, one of which is mounted in connection with the stationary support and the other of which is mounted in connection with the swinging member, one of said units comprising a casing, a re- 100 silient socket member mounted in said casing and exposed therethrough and the other of said units being provided with an anti-friction member adapted to enter said re- 105 silient socket member.

3. A device of the class described for use in connection with a swinging member mounted in a stationary support, said device being composed of separate units, one of which is mounted in connection with the stationary 110 support and the other of which is mounted in connection with the swinging member, one of said units comprising a casing, a re- 115 silient socket member mounted in said casing and exposed therethrough and the other of said units being provided with an anti-friction member adapted to enter said re- 120 silient socket member, and said socket member being provided with means for guiding the anti-friction member into the socket of said socket member.

4. A device of the class described for use in connection with a swinging member mounted in a stationary support, said device being composed of separate units, one of said units 125 being mounted in connection with the stationary support and comprising a socket member and the other of said units being mounted in connection with the swinging member and being provided with an anti- 130

- friction device, and resilient means in said first named unit adapted to receive the anti-frictional device of the last named unit whereby in the operation of opening the 5 swinging member will be aided by the resilient means of said first named unit.
5. A device of the class described for use in connection with a swinging member mounted in a stationary support, said device being 10 composed of separate units, one of said units being mounted in connection with the stationary support and comprising a socket member, the other of said units being mounted in connection with the swinging member 15 and being provided with an anti-friction roller, and tensional means in said socket member in connection with which said anti-friction roller is adapted to operate in the operation of closing said swinging member.
- 20 6. A device of the class described for use in connection with a door and door frame, said device comprising an anti-friction roller mounted in connection with the door and a socket member mounted in the door frame and into which said antifriction roller is 25 adapted to pass, and resilient means in said socket member adapted to operate in connection with said anti-friction roller to hold the door in the door frame under tension and to aid in releasing the door from the door frame 30 in the operation of opening the same.

In testimony that I claim the foregoing as my invention I have signed my name in presence of the subscribing witnesses this 23rd day of April, 1921.

JOSEPH SOSS.
